TABLE CONSTRUCTION

William A. Hillenbrand, Franklin County, Ind.,
assignor to Hill-Rom Company, Inc., Batesville,
Ind., a corporation of Indiana

Application December 12, 1945, Serial No. 634,484

1 Claim. (Cl. 311—38)

1

This invention relates to tables and is particularly directed to an improved top structure preferably for use in overbed tables of the type used in hospitals. Although this invention is directed primarily to use in overbed tables, it is not intended to limit the invention to this use.

The present invention constitutes an improvement of structure of the type shown in the previous patent to William A. Hillenbrand, No. 2,346,919, issued April 18, 1944. As shown in the patent, the top structure includes a main top element having an opening in its central forward part within which is fitted a movable top section. The movable top section has been hinged to the top and has also been pivotally mounted on the hinge so that it could be placed in any inclined position and could be reversed so as to dispose forwardly either a mirror element or a plain book rest as desired.

The particular purpose of the present invention has been to improve the arrangement of the section and the hinges. The arrangement of the hinges in the past has necessitated an unsightly space between the ends of the section and the opening within which it fits.

Therefore, it has been an object of the present inventor to provide an improved hinged connection between the movable section and the top of the table whereby the unsightly spaces between the ends of the section and the adjacent ends of the opening in the table top are eliminated. More particularly, the purpose has been to form the hinges in an improved manner and to attach them to the top and the hinged top section in relation to clearance notches which receive the hinges and permit them to nest therein when the top section is in position flush with the top of the table, that is to say, in position of non-use.

It has been a further object of the present inventor to provide a novel hinge structure, particularly as to the shape of the hinges whereby they will move into neat, snug-fitting relationship between the top and the section whereby the ends of the section and the adjacent surfaces of the opening in the top are in abutment, or substantial abutment.

Other objects and certain advantages of the invention will be more fully apparent from a description of the drawings, in which:

Figure 1 is a top plan view of the improved table top.

Figure 2 is a side view thereof showing the top fragmentarily with respect to the upright and the balance of the table structure.

Figure 3 is an enlarged fragmentary view taken

from Figure 1 showing the appearance of one of the hinges when it is nested within a notch or slot when the hinged section is in position flush with the top of the tables.

5 Figure 4 is an enlarged sectional view taken on line 4—4, Figure 1, showing the details of the invention.

Figure 5 is a sectional view taken on line 5—5, Figure 4, showing the combination book rest and 10 mirror element in position of non-use.

Figure 6 is a sectional view taken on line 6—6, Figure 4, showing the hinged section in position of use of the mirror with the hinges functioning to support the same.

15 Figure 7 is a sectional view taken on line 7—7, Figure 1, detailing the pivot bracket connecting the end of a hinge to the pivotally hinged section.

Figure 8 is a sectional view taken on line 8—8, Figure 6, detailing one of the rear pivotal connections of the hinged section to the main top element.

Figure 9 is a fragmentary sectional view taken on line 9—9, Figure 6, showing one of the rear hinge connections.

25 The table structure will not be described except as is necessary for an understanding of the invention. For this reason, only the top structure of the table is shown.

Referring to the drawings, the top is indicated 30 generally at 10. It is supported on an elongated tubular member 11 formed in the shape of an elongated loop and having its adjacent ends welded to a bracket 12 at the top of the post or upright 13. The crank 14, illustrated, is for the 35 purpose of raising and lowering the table top.

The main portion of the top is made in one piece which is indicated at 15. An opening 16 of rectangular form is provided in the central forward part of the table top. The movable section 40 17 constituting a combination book rest and mirror element fits snugly within this opening. Normally, the element 17, when in position of non-use, is disposed with its upper surface flush with the upper surface of the top element.

45 A sheet metal stamping 18 is provided and is secured beneath the table top. This stamping is pan-shaped and includes a marginal flange 19 extended around its ends and inner side. The pan is attached in position by means of screws extended through this flange into the underside of the top around the margin of the opening 16. At the front of the pan, the flange is dispensed with and the upper edge of the front side of the pan is turned to provide a stiffening lip 20. When 50 secured in position, the forward edge of the pan

lies against the forward run of the tubular support element 11. The ends of the pan are depressed adjacent the end flanges to provide depressions 21 for containing and supporting stops or abutment strips 22. These strips consist of elongated pieces of rubber incorporating cross-notches 23 adjacently arranged in the respective strips.

The hinged section is rectangular and carries an oval mirror 24 on one side thereof. Hinge brackets 25 are provided at the respective ends of the section centrally of these ends. Since the side carrying the mirror is normally the underside of the section, the flanges 26 (see Figure 7) of the brackets are disposed on the side carrying the mirror and are countersunk in the material of the section. They are held in position by means of screws 27. The side flanges 28 of the brackets, which carry the pivot or hinge pins 29, are also countersunk so as to permit the hinge 30 to lie flush with the end of the section. The pivot pin is fixed in the flange of the bracket and has its outer end provided with a formed head 31 engaged in an enlarged end of the bore in the hinge.

The hinges 30 have their outer ends attached as described above. The rear or inner ends of the hinges are pivotally connected to the main top element on the underside thereof immediately adjacent and to the rear of the inner corners of the opening. Brackets 32, similar to those employed for attaching the hinges to the pivoted element are employed. The vertical flanges of these brackets 32 extend upwardly into the underside of the table top in slots 33, which slots also provide clearance for the pivoted connection of the hinges to the brackets. The rear pivot pins are indicated at 34 and their mounting and attachment is the same as that of the pins 29.

The hinges extend through openings 35 in the metal pan at the inner margin of its flanges. Each hinge element has an arcuate portion 36 formed on a radius taken from the center of the rear pivot (see Figure 6) so that upon movement of the hinge about this pivot, the arcuate portion will traverse the opening which need be no more than slightly greater in width than the width of the arcuate portion.

The ends of the openings 16 are notched as at 37-37 so as to receive the straight portions 38 of the hinges when the section is in position of non-

use (see Figure 5). These notches are of a depth equal to the thickness of the hinge material and since the hinges engage the hinged section flush with its end surfaces, the result is that the pivoted section will fit snugly in its opening 16 and the straight portions of the hinges will nest within the notches or slots.

The rear ends of the hinges adjacent the rear pivots are connected by a cross bar 39, which will cause the hinge elements to move in unison and will stiffen the hinged and pivoted mounting of the movable section.

As shown in the top plan view, Figure 1, there is no open space or gap between the pivoted section 17 and the adjacent surfaces of the opening 16. Further, the hinges have been designed so as to move easily with respect to the top, particularly at those points at which they pass through the pan structure to permit the rear pivotal connection to the underside of the table top.

Having described my invention, I claim:

In a table top structure, a supporting frame, a top element on said supporting frame, an adjustable section disposed centrally of the top element within an opening thereof, said section fitting closely within the opening, hinges pivotally and rotatively connecting said section to the underside of the table top and clearance notches in the side surfaces of the opening, said hinges consisting of links having inner end portions of arcuate form disposed on the axes of the pivotal connections to the table top and straight portions extending from the arcuate portions to the connections on the movable top section, and a bar connecting the hinges at their portions adjacent the pivotal connections to the table top, said straight portions adapted to nest in the notches when the section is within the opening.

WILLIAM A. HILLENBRAND.
